WATER WALL BOILER

George W. Heald and Audrey J. Popham,
Chicago, Ill.

Application September 9, 1935, Serial No. 39,693

6 Claims. (Cl. 122—336)

This invention relates to boilers, and has to do with water tube boilers provided with water walls.

It is an object of our invention to provide a boiler structure embodying a water tube boiler provided with water walls, such boiler being of high efficiency, exceptionally compact construction and low head-room, and rapid steaming.

A further object is to provide a boiler of the character stated having water walls included in the water circulatory system and cooperating with certain of the other tubes of the boiler structure to define a combustion space of considerable volume so disposed that the boiler as a whole has exceptionally low head-room.

15 Further objects and advantages of our invention will appear from the detail description.

In the drawings:

Figure 1 is a front view, partly broken away and in section, of a boiler structure embodying our invention, the broken-away portion of this figure being sectioned substantially on line 1—1 of Figure 2;

Figure 2 is a sectional view taken from front to back of the boiler structure substantially in the plane of line 2—2 of Figure 1;

Figure 3 is a fragmentary sectional view of the boiler taken from front to back thereof substantially in the plane of line 3—3 of Figure 1, parts being broken away and parts being omitted for clearness of illustration; and

Figure 4 is a fragmentary vertical sectional view through the boiler from front to back thereof, taken substantially in the plane of line 4—4 of Figure 1, parts being omitted for clearness of illustration.

The boiler structure, in its entirety, comprises the boiler proper and the setting therefor, including the furnace. The setting S may be of any suitable or preferred type and includes a furnace defining a combustion chamber 1 beneath which extends a grate 2 adjacent the rearward end of which a bridge wall 3 extends transversely of the combustion chamber. The bridge wall and the grate and adjacent portions of the furnace define the fire-box 4, to which fuel may be supplied by a stoker 5 of suitable type, or in any other suitable manner. The particular manner of supplying fuel to the furnace is not of the essence of our invention, nor is the type of fuel used, it being understood that any suitable fuel supplied to the furnace in any well known or suitable manner may be utilized. The furnace is, in general, cubiform, side walls 6 thereof defining the sides of the combustion chamber 1.

55 The boiler proper is suitably supported in the

setting S. This boiler comprises two upper steam and water drums 7 and 8 disposed adjacent the front and the rear of the furnace, respectively, and a lower mud drum 9 disposed in rear of bridge wall 3 and in substantial vertical alignment with drum 8. Drums 7 and 8 are connected by a bank of water tubes 10 opening into these drums below the normal water line therein, indicated in Figure 2, and drums 8 and 9 are connected by a bank of tubes 11. Mud drum 9 is connected to drum 7 by a bank of tubes 12, these tubes being of approximately L-shape lengthwise and having their lower arms disposed vertically and substantially parallel to tubes 11 of the rear bank. The upper arms of tubes 12 are inclined upwardly and forwardly toward drum 7, as shown in Figure 2, and these arms are alternately depressed so that each is vertically spaced from the next adjacent arm, as shown. The three banks of tubes thus connect the drums in a ring flow circuit, this arrangement being conducive to rapid circulation of the water, which assures wet tubes, maximum heat transference, and resulting high efficiency and rapid steaming.

In order to prevent objectionable heating of the furnace walls 6, with injurious effect thereto, we provide adjacent the inner face of each side wall of the furnace a water wall. This water wall comprises a plurality of water tubes consisting of two sets of tubes. The tubes of one set, designated 13, extend from the mud drum 9, adjacent the end thereof, to the drum 7 adjacent the corresponding end of the latter. The tubes 13 are of approximately L-shape lengthwise and are disposed reversely to tubes 12, the lower arms of tubes 13 being inclined upward and forward from mud drum 9 and the upper arms of these tubes being disposed substantially vertical and extending upward toward drum 7. The end portions of tubes 13 are connected into the drums 7 and 9, the terminal portions of these tubes being bent so as to enter the drums radially, as is known in the art. Tubes 14 of the other set of tubes of the water wall connect the mud drum 9 to the rear upper drum 8. These tubes 14 are of approximately U-shape lengthwise and have their bight portions disposed substantially vertical and parallel to the vertical arms of tubes 13. The tubes 13 and 14 thus form a water wall of approximately rectangular shape and considerable area. It will be noted, from Figure 2, that the upper arms of tubes 12 are disposed between the water walls and extend transversely of the tubes of the latter at approximately the upper ends of certain of the water wall tubes. It will also be

noted that the tubes 12 and the water wall define a combustion space 15 of considerable volume, this combustion space corresponding in width to the distance between the water walls and having a height approximately equal to the vertical distance between the mud drum 9 and the front upper drum 7. The water walls absorb the radiant heat from the fire within the furnace, thus shielding the side walls of the furnace from objectionable heating, while utilizing this radiant heat to best advantage for heating the water. This results in a boiler of exceptionally high efficiency and capacity, and which steams exceedingly rapidly. A further advantage is that by forming the combustion space 15 by means of the water walls and the bank of tubes connecting the mud drum to the front upper drum, the boiler is of unusually compact construction and low head-room and is, therefore, well suited for installation in places having limited head-room and where a rapid steaming boiler of large capacity is required.

The top of the furnace is closed by a refractory tile roof 16 extending between the drums 7 and 8. A tile baffle 17 extends from the top of bridge wall 3 upward between the two front rows of tubes of bank 11, and a supplemental baffle 18 extends upward and forward from the upper end of baffle 17, this supplemental baffle conveniently resting upon the lower ones of the upper arms of tubes 12. A baffle 19 extends downward from drum 8 centrally of the rear bank of tubes, and a baffle 20, disposed in rear of baffle 19, extends lengthwise of the rear bank of tubes and terminates a short distance from drums 8 and 9. The products of combustion may escape from the furnace through an outlet 21 leading to a breeching and controlled by a damper 22.

Steam tubes 23 connect drum 8, at the upper portion thereof, to a steam manifold 24 disposed within drum 7, adjacent the top thereof, and closed to the interior of this drum. A baffle 25 is disposed within drum 8 adjacent the ends of tubes 23. Manifold 24 is connected by steam tubes 26 to manifold 27 of a superheater 28, comprising a second manifold 29 and tubes 30 connecting the manifolds 27 and 29 and extending downward into the furnace between the tubes of the rear bank, as in Figure 2. Manifold 29 of the superheater is connected to suitable steam take-off means, in a known manner.

Drums 7 and 8 are connected by steam tubes 31 opening into the upper portions of these drums and conveniently disposed in the plane of tubes 23. The respective tubes 23 are of the same cross sectional area as the respective tubes 31, but the latter tubes are materially greater in number than tubes 23. We find that the total capacity of the tubes 31 should preferably approximate one and one-half times the capacity of the tubes 23. Assuming there to be fourteen of the tubes 23, there should be twenty-one of the tubes 31, if the respective tubes 31 are of the same cross-sectional interior area as the respective tubes 23. Since the tubes 23 are materially less in number than the tubes 31, steam header 24, which corresponds approximately in length to the baffle 25, extends but approximately one-third of the length of drum 7, as will be clear from Figure 1.

A baffle 32 is disposed within the upper portion of drum 7 and extends across the ends of tubes 31, and a baffle 33 is similarly disposed in drum 8, it being noted that the opening between this latter baffle and the wall of the drum is much greater than the opening between baffle 32 and

the wall of drum 7. The baffle 33 is to facilitate separation of moisture from the steam, whereas the baffle 32 is to prevent entry of water with the steam from drum 7.

It will be noted that steam can flow readily through the twenty-one tubes 31 from drum 7 into drum 8, whereas flow of steam from the latter drum through the fourteen tubes 23 is relatively reduced. This has the effect of creating within drum 8 a somewhat higher pressure than that which exists within drum 7. This is desirable as being conducive to maintaining the water at the proper level within drums 7 and 8, particularly when the boiler is steaming rapidly. Due to the exceedingly high speed of circulation of the water through the water walls and the banks of water tubes, there is a tendency, in some cases, to pile up the water in drum 8, raising the water level therein to an objectionable extent while objectionably lowering the water level in drum 7. When this occurs, priming is apt to result, and there is also the possibility that water may be withdrawn from the upper portions of the tubes connected to drum 7 to such an extent as to cause dry tubes, with resulting steam locking and other difficulties. We find that the possibility of these difficulties arising, under unfavorable conditions, may be avoided by creating a somewhat higher pressure in drum 8 than in drum 7, in the manner above stated. In some instances this may not be necessary, but we prefer creating a difference in pressure between the drums 7 and 8 for the reasons above noted, as a precautionary measure.

What we claim is:

1. In a boiler structure, a setting defining a furnace and a combustion chamber therein, a boiler comprising a lower rear mud drum and two upper steam and water drums adjacent the front and the back of the furnace, a plurality of tubes disposed in proximity to the inner face of each side wall of said furnace and providing a water wall therefor, each of said plurality of tubes comprising two sets of tubes, the tubes of one set being of approximately L-shape lengthwise with lower arms connected to and extending upward and forward from said mud drum and substantially vertical upper arms extending toward and connected to said front upper drum, the tubes of the other set connecting said mud drum to said rear upper drum and being of approximately U-shape with their bight portions disposed substantially vertically, a bank of water tubes connecting said two upper drums, a bank of tubes connecting said rear upper drum to said mud drum, and a bank of tubes of approximately L-shape lengthwise connecting said mud drum to said front upper drum, the lower arms of the tubes of the last named bank being substantially vertical and the upper arms thereof extending upward and forward between said water walls substantially at the upper ends of the vertical arms of certain of the tubes of said water walls.

2. In a boiler structure, a setting defining a furnace and a combustion chamber therein, a boiler comprising a lower rear mud drum and two upper steam and water drums adjacent the front and the back of the furnace, a plurality of tubes disposed in proximity to the inner face of each side wall of said furnace and providing a water wall therefor, each of said plurality of tubes comprising two sets of tubes, the tubes of one set being of approximately L-shape lengthwise with lower arms connected to and extending upward and forward from said mud drum and sub-

- stantially vertical upper arms extending toward and connected to said front upper drum, the tubes of the other set connecting said mud drum to said rear upper drum and being of approximately U-shape with their bight portions disposed substantially vertically, a bank of water tubes connecting said two upper drums, a bank of tubes connecting said rear upper drum to said mud drum, and a bank of tubes of approximately L-shape lengthwise connecting said mud drum to said front upper drum, the lower arms of the tubes of the last named bank being substantially vertical and the upper arms thereof extending upward and forward between said water walls substantially at the upper ends of the vertical arms of certain of the tubes of said water walls, said last named bank of tubes defining with the water walls a box like combustion space and the upper arms of the tubes of said last named bank being alternately depressed and forming a slag screen over said space.
3. In a boiler of the character described, a front upper drum, a rear upper drum, a lower mud drum, a bank of water tubes connecting said two upper drums, a bank of tubes connecting said rear upper drum to said mud drum, a plurality of tubes adjacent each end of said drums defining water walls, each of said plurality of tubes comprising two sets of tubes, the tubes of one set being of approximately L-shape lengthwise with lower arms connected to and extending upward and forward from said mud drum and substantially vertical arms extending toward and connected to said front upper drum, the tubes of the other set connecting said mud drum to said rear upper drum and being of approximately U-shape with their bight portions disposed substantially vertically, and a bank of tubes of approximately L-shape lengthwise connecting said mud drum to said front upper drum, the lower arms of the tubes of the last named bank being substantially vertical and the upper arms thereof extending upward and forward between said water walls substantially at the upper ends of the vertical arms of certain of the tubes of said water walls.
4. In a boiler of the character described, a front upper steam and water drum, a rear upper steam and water drum, a lower mud drum, banks of water tubes connecting said drums in a ring flow circuit, water walls adjacent the ends of said drums each comprising two sets of water tubes, the tubes of one set connecting said mud drum to said front upper drum and the tubes of the other set connecting said mud drum to said rear upper drum, a plurality of steam tubes connecting said two upper drums, and a plurality of steam take-off tubes connected to said upper rear drum and of materially less total capacity than the steam tubes connecting said two upper drums.
5. In a boiler of the character described, a front upper steam and water drum, a rear upper steam and water drum, a lower mud drum, banks of water tubes connecting said drums in a ring flow circuit, water walls adjacent the ends of said drums each comprising two sets of water tubes, the tubes of one set connecting said mud drum to said front upper drum and the tubes of the other set connecting said mud drum to said rear upper drum, a plurality of steam tubes connecting said two upper drums, a steam header within said front upper drum and closed to the interior thereof, a plurality of steam tubes connecting said rear upper drum to said header and of materially less total capacity than the steam tubes connecting said two upper drums, and steam take-off means connected to said header.
6. In a boiler of the character described, a front upper steam and water drum, a rear upper steam and water drum, a lower mud drum, banks of water tubes connecting said drums in a ring flow circuit, water walls adjacent the ends of said drums each comprising two sets of water tubes, the tubes of one set connecting said mud drum to said front upper drum and the tubes of the other set connecting said mud drum to said rear upper drum, a plurality of steam tubes connecting said two upper drums, a steam header within said front upper drum and closed to the interior thereof, a plurality of steam tubes connecting said rear upper drum to said header and of materially less total capacity than the steam tubes connecting said two upper drums, and a superheater connected to said header.

GEORGE W. HEALD.
AUDREY J. POPHAM.
